**IMPACT ENERGY ABSORBING MECHANISM
FOR RAILWAY VEHICLES**
James C. Settles, Columbus, Ohio, assignor to The Buck-
eye Steel Castings Company, Columbus, Ohio
Filed June 9, 1958, Ser. No. 740,785
12 Claims. (Cl. 213—8)

The present invention relates to hydraulic energy absorbing means in association with a railway vehicle body and more specifically pertains to liquid cushioning means in operative relationship with the couplers and draft riggings of a railway freight car to provide means for absorbing and dissipating the kinetic energy inherent in impact engagement of the couplers which occurs during coupling operations between cars, in train operation, in switching and humping operations, or in any type of collisions wherein an impact is applied to either or both couplers.

An object of the present invention is to provide an energy absorbing mechanism in association with known draft riggings and with a conventional center sill structure of a railway freight car wherein liquid forms an element of the energy absorbing means and its flow through a restricted passage or passages during collision is metered to cushion movement of the coupler and elements making up the invention relative to the center sill structure whereby substantially all of the kinetic energy of the collision is absorbed by the motion of the liquid and thereafter dissipated as heat from the liquid.

Another object of the invention is to provide an auxiliary center sill structure which may be mounted within a conventional double Z center sill structure of existing or new cars with the auxiliary sill structure adapted to move longitudinally of the standard sill structure with the hydraulic means accommodated within the sill assembly and actuated upon movement of the auxiliary sill structure relative to the fixed sill structure to cushion impacts in either direction and to substantially reduce the magnitude of the forces transmitted to the vehicle body.

A more specific object of the invention is to provide a plurality of double acting hydraulic devices in association with the couplers and draft riggings of a railway vehicle through which an impact applied to one or both couplers and in either direction is transmitted to cushion and substantially dissipate the energy of the impact and thereby control the magnitude of the force exerted upon the fixed sill structure and vehicle body with the hydraulic devices and the elements associated therewith accommodated in or housed within a standard sill structure for the railway vehicle.

Other and further objects and features of the invention will be appreciated and become apparent to those skilled in the art to which the invention pertains and as the present disclosure proceeds and upon consideration of the accompanying drawings and the following detailed description wherein an exemplary embodiment of the invention is disclosed.

In the drawings:

FIG. 1 is a side elevational view of the lower portion of a railway freight car provided with hydraulic impact energy absorbing means exhibiting the invention for both couplers thereof.

FIG. 2 is a vertical section on a larger scale taken along the longitudinal center of the sill assembly showing the portion thereof indicated at 2 in FIG. 1.

FIG. 3 is a similar sectional view of that portion of

2

the sill assembly and the absorbing mechanism indicated at 3 in FIG. 1.

FIG. 4 is a sectional plan view of the sill assembly and that portion of the absorbing mechanism shown in FIG. 2.

FIG. 5 is a sectional plan of the portion of the energy absorbing mechanism and sill assembly shown in FIG. 3.

FIG. 6 is a sectional plan view similar to FIG. 4 showing displacement of the coupler and parts associated therewith to the full closure position and to the right with respect to the fixed sill structure.

FIG. 7 is a sectional plan view similar to FIG. 5 showing the movable sill structure displaced to the full closure position to the right relative to the fixed sill structure.

FIG. 8 is a sectional plan view of that portion of the energy absorbing means indicated at 8 in FIG. 1 and showing the position of the parts in the full closure position to the right.

FIG. 9 is a transverse sectional view executed on a still larger scale and taken on the line 9—9 of FIG. 2.

FIG. 10 is a transverse sectional view taken on the line 10—10 of FIG. 2.

FIG. 11 is a transverse sectional view taken on the line 11—11 of FIG. 2.

FIG. 12 is a transverse sectional view taken on the line 12—12 of FIG. 2.

FIG. 13 is a transverse sectional view taken on the line 13—13 of FIG. 3.

FIG. 14 is a transverse sectional view taken on the line 14—14 of FIG. 3.

The invention pertains to hydraulic means in association with a railway car and the couplers thereof which acts to cushion impacts applied to one or both couplers. The arrangement of the hydraulic means is such that the absorbing mechanism operates during the application of buffing or pulling impact forces applied to either coupler of the railway vehicle. The embodiment of the invention disclosed includes two hydraulic devices one associated with each end of a railway vehicle both of which act to cushion impacts in either direction and the entire hydraulic absorbing mechanism is so constructed that it may be applied within a standard double Z type center sill structure fixed to existing or new car bodies.

Referring to the drawings there is represented in FIG. 1 a railway car body 16 which is equipped with a conventional double Z type center sill structure 17 and which forms a part of the underframe of the railway car body 16. The center sill structure 17 is attached to the car body and may be regarded as the fixed sill structure. In carrying out the invention an auxiliary center sill structure 18 is arranged within the fixed sill structure 17 so that the auxiliary sill assembly may move longitudinally of the car body and relative to the fixed sill structure 17. The slideable auxiliary sill structure 18 consists of a pair of spaced channel members 19 with top and bottom cover plates at spaced intervals along the length of the movable sill structure 18. The channel members 19 form the major elements of the auxiliary sill structure 18 and extend continuously throughout the length of the railway vehicle and project beyond each end of the fixed sill structure a predetermined distance in order to accommodate relative sliding movements of the sill structures during a collision. The normal or neutral position of the auxiliary sill structure 18 as it projects beyond the ends of the railway car body 16 is shown in FIG. 1.

A striker casting 21 is provided at each end of the auxiliary sill structure 18 having a coupler carrier 22 (FIG. 2) thereon for supporting the stem 23 of a railway coupler 24 of the knuckle type. The auxiliary sill struc-

70

ture 18 carries front draft lugs 26 and rear draft lugs 27 as best shown in FIGS. 4 and 6. Each coupler is provided with a conventional type of draft rigging which includes a yoke 28 and a resilient draft gear as represented by phantom lines 29 and the usual front and rear followers 31 and 32. The coupler and the yoke and the draft gears are assembled and arranged within each end of the auxiliary sill structure 18 and cooperate in the usual manner with the coupler carrier 22 and the front draft lugs 26 and the rear draft lugs 27. The inner ends of each pair of rear draft lugs 27 are joined by a transversely disposed member 33 which serves to limit the total relative movement of the auxiliary sill structure 18 relative to the fixed sill structure 17 and this feature will be appreciated as the present disclosure proceeds.

The wheels 35 of the trucks for the vehicle body 16 are represented in FIG. 1 and a body center plate 36 is provided at the truck center which is secured to the fixed sill structure 17 as best illustrated in FIGS. 2 and 4. The center plate 36 includes lateral portions 37 which extend under the sill structure 17 and under the body bolster bottom cover plate 38 which extends under the fixed sills at this location and is secured to the horizontal flanges of the double Z center sill structure 17. The body center plate 36 and its lateral portions 37 are reinforced by a pair of transversely extending beams 39 which extend under the outturned flanges of the sill structure 17. A center post indicated generally at 40 is formed of two parts 41 and 42 for convenience in application to the sill structure. The lower part 42 of the center post may be formed integral with the center plate 36 while the upper part 41 may be attached by any suitable means such as welding to the top web of the fixed center sill structure 17. The outer vertical face 43 as provided by the upper and lower parts of the center post structure forms a stop which cooperates with the member 33 forming a part of the rear draft lugs 27 to limit relative movements of the sliding sill structure and the fixed sill structure. The inner vertical face 44 (FIG. 2) as provided on the upper and lower parts 41 and 42 of the center post structure cooperates with and forms an abutment for one end of a piston rod 48 for one of the hydraulic mechanisms.

One hydraulic device is positioned inwardly of the center post structure 40. Another hydraulic device of similar construction is associated with the sill assembly for the coupler 24R and draft rigging at the other end of the railway vehicle. Each hydraulic device is of identical construction and an appreciation of the structural characteristics of one provides an understanding of the nature and mounting of the other. One hydraulic device is shown in FIGS. 2, 4 and 12 in relationship with associated parts of the sill assembly. Each hydraulic device includes a cylinder 46 and a piston 47 mounted for reciprocating movements in the bore of the cylinder. The cylinder 46 is rugged construction but is of such exterior dimensions as to be accommodated within the area between the channel members 19 of the sliding sill structure 18. The piston rod 48 extends from each face of the piston 47 and is desirably formed integral therewith. Disc-shaped members 49 close the ends of the cylinder 46 and the piston rod 48 extends through each disc. The discs 49 are secured to the cylinder in liquid tight relationship. Any suitable means may be provided for sealing the piston rod 48 relative to the disc shaped members 49 so as to prevent leakage of liquid from the cylinder under the pressures required for absorbing the impact energy.

An energy absorbing mechanism exhibiting the invention includes means preventing endwise movements of the cylinder 46 with respect to the auxiliary sill structure 18. The cylinder 46 has external dimensions to fit snugly between the channel members 19 as shown in FIG. 12 and the cylinder is in part supported by a plate 51 which may be attached to the lower inturned flanges of the channel members 19 by means of flat headed screws 52. A plate

50 overlies the cylinder 46 and this plate may be welded to the upper flanges of the channel members 19 as shown in FIGS. 11 and 12. The cylinder is carried by the auxiliary sill structure 18 and is further supported for sliding movements relative to the fixed sill structure by a plate 55 which may be secured to the outturned flanges 71 of the center sill by rivets 60. The plate 55 is maintained in spaced relation below the flanges 71 to accommodate the plate 51 by means of filler plates 65. A pair of lugs 53 are in abutting relationship with one end of the cylinder 46 as shown in FIG. 4 and these lugs are attached by any suitable means such as welding to the channel members 19 of the auxiliary sill structure 18. A similar set of lugs 54 are in abutting relationship with the other end of the cylinder 46. These lugs may be welded or otherwise secured to the channel members 19 which form the principal elements of the auxiliary sill structure 18. The lugs 53 and the lugs 54 provide means preventing endwise movement of the cylinder with respect to the auxiliary sill structure so that the cylinder 46 is moved with respect to the fixed sill structure 17 and with respect to the car body 16 upon longitudinal displacement of the auxiliary sill structure 18 with respect to the fixed sill structure 17.

In the normal or neutral position of the auxiliary sill structure 18 with respect to the fixed sill structure 17 the piston 47 occupies a position substantially midway between the ends of the cylinder 46. The interior surface of the cylinder 46 is of cylindrical shape and the piston 47 is adapted for axial movements relative to the cylinder. The wall of the cylinder 46 is provided with metering grooves 58. These grooves may be formed with constant width throughout the length of the cylinder. The depth or radial dimension of each groove may be uniform throughout the center portion of the cylinder for a distance equal to the width of the piston 47. From these points to the respective ends of the cylinder the metering grooves 58 decrease in depth. These grooves may take other forms wherein the cross section decreases in proceeding towards the ends of the cylinder in a manner as required to produce the desired closure curve. The rate of decrease in depth or reduction in cross section of each groove may be determined mathematically to produce the metering effect desired for cushioning movements of the cylinder 46 relative to the piston 47 in either direction in response to movements of the auxiliary sill structure 18 relative to the fixed sill structure 17. The cylinder 46 is filled with liquid which may be introduced through a fill opening 59 (FIGS. 2 and 12) which may be closed by a threaded plug 61. One channel member 19 and the associated vertical side web of the fixed sill structure 17 are provided with slots 62 for the removal of the plug 61 and the introduction of liquid into the fill opening 59. The filling operation is desirably carried out in the neutral position of the auxiliary sill structure with respect to the fixed sill structure when the slots 62 are in registration.

The outer end of the piston rod 48 is in abutting relationship with the inner face 44 of the center post 40 and remains in such abutting relationship throughout all operating conditions. The inner end of the piston rod 48 is in abutting relationship with the outer face 70 (FIG. 3) of a stop member indicated generally at 64 and comprising two block shaped elements 66 and 67. This stop member is formed of two parts for convenience in application and attachment to the fixed sill structure 17. The upper element 66 is welded to the top web of the center sill structure as best shown in FIGS. 3 and 13. The lower block shaped element is attached in a suitable manner such as welding indicated at 68 to a plate 69 which is in turn attached to the outturned lower flanges 71 of the fixed sill structure by means of rivets 72 or the like. The block shaped elements forming the stop member 64 are of such dimensions measured transversely of the sill assembly as to be accommodated between the inturned upper and lower flanges of the channel members 19.

Thus the piston rod 48 having its outer end in abutting relationship with the inner face 44 of the center post 40 and its inner end in abutting relationship with the outwardly directed face 70 of the stop member 64 remains in a fixed position with respect to the fixed sill structure 17 and with regard to the car body 16.

A recoil spring 73 is arranged centrally of the car body and accordingly occupies a generally mid position with respect to the length of the sill assembly. The spring 73 is desirably of a helical type having a diameter so as to be accommodated within the sill assembly and between the inturned flanges of the channel members 19 of the auxiliary sill structure 18 as best shown in FIG. 14. One end of this spring or resilient means 73 engages a follower 74 having a spring positioning ring 76 thereon. Another follower 77 is provided in engagement with the other end of the helical spring 73 and the follower 77 has a spring positioning ring 78 thereon. A plane surface of the follower 74 is in engagement with abutment means indicated generally at 79 (FIG. 3) and a plane surface of the follower 77 is in engagement with abutment means indicated generally at 81. The abutment means 79 and 81 each comprise an upper block-shaped element 82 and a lower block-shaped element 83. These abutment means are formed of two elements for convenience in application and attachment to the fixed sill structure 17. The block elements 82 are secured to the top horizontal web of the fixed sill structure 17 in any suitable manner such as by means of welding. The lower block-shaped elements 83 are attached in any suitable manner such as welding to a shear plate 84 which is in turn attached to the outturned flanges 71 of the fixed sill structure by means of rivets 86. The block-shaped elements 82 and 83 are each of such dimensions measured transversely thereof as to be accommodated between the inturned upper and lower flanges of the channel members 19 as shown in FIGS. 5 and 14.

A pair of lugs 87 (FIG. 5) are attached to the channel members 19 of the auxiliary sill structure and these lugs in the normal or neutral position of the auxiliary sill structure 18 with respect to the fixed sill structure 17 engage opposite side edge portions of the follower 74. The lugs 87 may be welded or otherwise securely attached to the auxiliary sill structure 18. A similar pair of lugs 88 are attached to the channel members 19 of the auxiliary sill structure as best shown in FIG. 5. The lugs 88 in the normal or neutral position of the auxiliary sill structure 18 with respect to the fixed sill structure are in abutting relationship with side edge portions of the follower 77. The space between the confronting edges of the lugs 87 and the space between the confronting edges of the lugs 88 is sufficient to accommodate the abutment means 79 and 81 therebetween. The spring 73 serves to resiliently maintain the auxiliary sill structure 18 in a normal or neutral position with respect to the fixed sill structure 17. This position is attained by the spring 73 urging the followers 74 and 77 respectively in engagement with the abutment means 79 and 81. Any movement of the auxiliary sill structure 18 with respect to the fixed sill structure in either direction further compresses the spring 73 in a manner such as illustrated in FIG. 7 wherein the lugs 87 have shifted the follower 74 to the right to compress the spring 73 because the follower 77 is prevented from moving to the right by the abutment means 81. The purpose of the spring 73 is to provide resilient means for restoring the auxiliary sill structure to a neutral or normal position after the energy of an impact has been dissipated. The spring 73 serves to restore the auxiliary sill structure to a neutral position with reference to the fixed sill structure in either direction of longitudinal movement of the auxiliary sill structure.

The closed ends of the cylinder 46 engage the lugs 53 and the lugs 54 in a normal or neutral position of the parts as shown in FIGS. 2 and 4. These lugs are secured

to the auxiliary sill structure 17. It is these lugs which move the cylinder 46 relative to the piston 47 and the force developed by such movement is controlled by the metering of the hydraulic device before it is transmitted to the car body. A similar hydraulic device and associated parts are provided within the sill assembly to the right of the center of the car body 16 shown in FIG. 1 and in association with the coupler 24R and the draft rigging at this end of the vehicle.

The extreme end portions of the channel members 19 are joined by a top cover plate 91. This plate terminates at 92 (FIG. 2) and the channel members 19 in the vicinity of the center post structure 40 are devoid of a top plate to permit sliding movement of the auxiliary sill structure 18 relative to the center post. A bottom plate 93 connects the lower portions of the channel members 19 of the auxiliary sill structure at the ends thereof and these plates (as shown in FIGS. 2, 9 and 10) may also be secured to the striker 21 and to the draft lugs 27 by means of flat headed screws. The plates 93 support the respective draft riggings including the yokes 28. The inturned upper flanges of the channel members 19 are shaped as indicated at 94 (FIG. 4) to permit the yoke 28 to swivel during horizontal angling of the coupler. The lower flanges of the channel members 19 are removed entirely in the regions 95 and 96 to permit application and removal of the yoke 28 and the draft gear 29 from the bottom side of the sill assembly. A bottom cover plate 97 is provided connecting the lower portion of the fixed sill structure 17 near the ends of the vehicle body 16. The plate 97 supports the overhanging ends of the auxiliary sill structure 18. The plate 97 is spaced below outturned flanges 71 by means of filler plates 98 as shown in FIGS. 9 and 10 to provide space for accommodating the plate 93. The plate 97 and the filler plates are secured to the flanges 71 by rivets 99.

As hereinabove indicated the auxiliary sill structure 18 and the fixed sill structure 17 and the couplers and their draft riggings are identical at both ends of the car body 16. The hydraulic device and the parts and elements co-operating therewith and described in association with the left hand end portion of the railway car body is also provided within that portion of the sill assembly to the right of the center of the car body shown in FIG. 1. Such an organization prevents any impact force from being applied to the body of the car except as metered through the hydraulic mechanisms. The combination operates to control the magnitude of the buffing forces and pulling forces and the conventional draft equipment at each end of the auxiliary sill structure functions to protect the auxiliary sill structure from high impact forces. While the conventional draft gears as employed in connection with the organization assist the hydraulic devices in absorbing the energy of collisions such draft gears are not significantly helpful in connection with high velocity collisions because of the lower capacity of the conventional type resilient draft gears.

In operation and upon the application of an impact in the direction of the arrow 101 (FIG. 6) the auxiliary sill structure 18 is displaced to the right relative to the fixed sill structure 17. Such a condition may develop as a result of a collision at the coupler 24 in FIG. 1 in a coupling operation or upon application of a sudden pull indicated by the arrow 102 (FIG. 8) applied to the coupler 24R. As a consequence of one or both of such influences the auxiliary sill structure 18 is displaced to the right relative to the fixed sill structure and the full stroke of such displacement is illustrated in FIGS. 6, 7 and 8. The draft gear 29 compresses an amount consistent with the force developed and follower 31 moves this distance to the right of its normal position. The follower 32 acting on the rear draft lugs 27 causes the auxiliary sill structure 18 to be moved to the right relative to the fixed sill structure 17 until the transverse member 33 contacts with the outer vertical face 43 of the center post structure 40 thereby

preventing further relative motion of the auxiliary sill structure 18 relative to the fixed sill structure 17.

The lugs 53 carried by the auxiliary sill structure 18 thus force the cylinder 46 to the right relative to the piston 47. The force developed by this hydraulic device is delivered through the piston rod 48 onto the stop member 64 and transferred to the fixed sill structure 17 and onto the car body. The lugs 53R (FIG. 8) carried by the auxiliary sill structure 18 also act, simultaneously with the lugs 53, against the end of cylinder 46R and move it to the right relative to the piston 47R. The force developed by this hydraulic device is transferred by the piston rod 48R onto the vertical inner face of the center post structure 40R and onto the car body 16 at this point. The spring 73 is compressed during such a stroke of the auxiliary sill structure and will recoil the auxiliary sill structure 18 to its normal or neutral position after the energy of the collision has been absorbed.

The assembly operates the same for relative movement between the auxiliary sill structure 18 and the fixed sill structure 17 in either direction. The two double acting cylinders operating simultaneously make it possible to design each cylinder small enough to permit their application within the space provided by a standard Association of American Railroads double Z center sill structure which is in use on existing freight cars and applied to new cars now being built. The grooves or orifices in the cylinders may be designed to produce as nearly as possible a rectangular force curve for substantially all car loads and at all speeds of approach producing an optimum condition of maximum energy absorption with minimum force and minimum closure. The structure disclosed provides the advantage that it can be metered to absorb the energy of collisions between cars of weights varying from an empty car up to a fully loaded one hundred ton capacity car without developing forces which are destructive to either the lading or the car structure. The force which each hydraulic mechanism must be metered to develop in order to absorb the energy of a given collision is inversely proportional to the maximum relative longitudinal movement which it is practical to provide between the auxiliary sill structure and the fixed sill or body.

While the invention has been described with reference to a particular type of railway vehicle provided with a conventional type of center sill structure it will be appreciated that the invention is adaptable to other types of railway vehicles and in connection with other types of draft riggings and sill structures. Such modifications and others may be made without departing from the spirit and scope of the invention as set forth in the appended claims.

What I claim and desire to secure by Letters Patent is:

1. A cushion mechanism for a railway vehicle for absorbing the energy of an impact applied to a coupler thereof comprising, a vehicle body, a center sill structure extending longitudinally of said body and secured thereto, an auxiliary sill structure extending lengthwise within said center sill structure arranged for movements longitudinally relative to said center sill structure, a coupler and a draft rigging carried by each end portion of said auxiliary sill structure, means coupling said draft riggings to said auxiliary sill structure for moving the auxiliary sill structure relative to said center sill structure upon application of an impact to either coupler, a cylinder mounted within said auxiliary sill structure, a piston within said cylinder, a piston rod extending through opposite ends of said cylinder, liquid within said cylinder, a center post structure secured to said center sill structure in abutting relationship with one end of said piston rod, stop means carried by the center sill structure in abutting relationship with the other end of said piston rod, lugs carried by the auxiliary sill structure engaging opposite ends of said cylinder preventing longitudinal movements of the cylinder relative to the auxiliary sill structure, and said cylinder having grooves therein controlling the velocity of flow of the liquid from one side of the piston to the other to cushion

movements of the auxiliary sill structure relative to the center sill structure.

2. A cushion mechanism for a railway vehicle for absorbing the energy of an impact applied to a coupler thereof according to claim 1, wherein the auxiliary sill structure includes channel members with the cylinder arranged therebetween, a plate joining said channel members under said cylinder, and a plate carried by the fixed sill structure in guiding relationship to the first plate.

3. A mechanism for absorbing the energy of an impact applied to a coupler of a railway vehicle comprising, a vehicle body, a center sill structure extending longitudinally of said body and secured thereto, an auxiliary sill structure extending lengthwise within said center sill structure arranged for movements longitudinally relative to said center sill structure, a coupler and a draft rigging carried by each end portion of said auxiliary sill structure, means coupling said draft riggings to said auxiliary sill structure for moving the auxiliary sill structure relative to said center sill structure upon application of an impact to either coupler, a double acting hydraulic device including a cylinder with a piston therein mounted within said auxiliary sill structure, a piston rod extending through opposite ends of said cylinder, a center post structure carried by said center sill structure in abutting relationship with one end of said piston rod, stop means carried by the center sill structure in abutting relationship with the other end of said piston rod, means carried by the auxiliary sill structure preventing longitudinal movements of said cylinder relative to the auxiliary sill structure, another double acting hydraulic device including a second cylinder with a piston therein mounted within the auxiliary sill structure, a second piston rod extending through opposite ends of the second cylinder, a center post structure carried by said center sill structure in abutting relationship with one end of the second piston rod, stop means carried by the center sill structure in abutting relationship with the other end of the second piston rod, means carried by the auxiliary sill structure preventing longitudinal movements of the second cylinder relative to the auxiliary sill structure, liquid within said cylinders, and means for controlling the flow of the liquid from one side of each piston to the other to cushion movements of the auxiliary sill structure relative to the center sill structure.

4. A mechanism for absorbing the energy of an impact applied to a coupler of a railway vehicle according to claim 3, including resilient means arranged within the auxiliary sill structure between said hydraulic devices, and means associated with said resilient means for returning the auxiliary sill structure to a neutral position with respect to the center sill structure upon completion of an impact stroke.

5. A mechanism for absorbing the energy of an impact applied to a coupler of a railway vehicle according to claim 3, including transverse members carried by the auxiliary sill structure for engagement with the respective center post structure to limit relative movements of the sill structure.

6. A cushion mechanism for a railway vehicle for absorbing the energy of an impact applied to a coupler thereof comprising, a vehicle body, a center sill structure extending longitudinally of said body and secured thereto, an auxiliary sill structure extending lengthwise within said center sill structure arranged for movements longitudinally relative to said center sill structure, a coupler and a draft rigging carried by an end portion of said auxiliary sill structure, means coupling said draft rigging to said auxiliary sill structure for moving the auxiliary sill structure relative to said center sill structure upon application of an impact to said coupler, a cylinder mounted within said auxiliary sill structure, a piston within said cylinder, a piston rod extending through opposite ends of said cylinder, liquid within said cylinder, means carried by the center sill structure in abutting relationship with one end of said piston rod, stop means carried by the center sill structure in abutting relationship with the other end of said piston rod, lugs carried by the auxiliary sill structure engaging opposite ends of said cylinder preventing longitudinal movements of the cylinder relative to the auxiliary sill structure, and said cylinder having grooves therein controlling the velocity of flow of the liquid from one side of the piston to the other to cushion

end of said piston rod, stop means carried by the center sill structure in abutting relationship with the other end of said piston rod, means carried by the auxiliary sill structure engaging opposite ends of said cylinder preventing longitudinal movements of the cylinder relative to the auxiliary sill structure, and means for controlling the flow of liquid from one side of said piston to the other side thereof to cushion movements of the auxiliary sill structure relative to the center sill structure.

7. A cushion mechanism for a railway vehicle for absorbing the energy of an impact applied to a coupler thereof according to claim 6, wherein the cylinder has a fill opening and the auxiliary sill structure has a slot therethrough aligned with the fill opening, and said center sill structure having a slot therethrough registering with the slot in the auxiliary sill structure when the sill structures are in a neutral position with respect to each other.

8. A cushion mechanism for a railway vehicle for absorbing the energy of an impact applied to a coupler thereof according to claim 6, wherein the auxiliary sill structure includes transversely spaced channel members having confronting flanges, and said cylinder being arranged between said channel members, and having an exterior cross section substantially filling the area between said channel members and the flanges thereof.

9. A mechanism for absorbing the energy of an impact applied to a coupler of a railway vehicle comprising, a vehicle body, a center sill structure extending longitudinally of said body and secured thereto, an auxiliary sill structure extending lengthwise within said center sill structure arranged for movements longitudinally relative to said center sill structure, a coupler and a draft rigging carried by each end portion of said auxiliary sill structure, means coupling said draft riggings to said auxiliary sill structure for moving the auxiliary sill structure relative to said center sill structure upon application of an impact to either coupler, a double acting hydraulic device including a cylinder with a piston therein mounted within said auxiliary sill structure, a piston rod extending through opposite ends of said cylinder, means carried by said center sill structure in abutting relationship with one end of said piston rod, stop means carried by the center sill structure in abutting relationship with the other end of said piston rod, means carried by the auxiliary sill structure preventing longitudinal movements of said cylinder relative to the auxiliary sill structure, another double acting hydraulic device including a second cylinder with a piston therein mounted within the auxiliary sill structure, a second piston rod extending through opposite ends of the second cylinder, means carried by said center sill structure in abutting relationship with one end of a second piston rod, stop means carried by the center sill structure in abutting relationship with the other end of the second piston rod, means carried by the auxiliary sill structure preventing longitudinal movements of the second cylinder relative to the auxiliary sill structure, liquid within said cylinders, and means for controlling the flow of the liquid from one side of each piston to the other to cushion movements of the auxiliary sill structure relative to the center sill structure.

10. In combination, an underframe structure having a guideway extending lengthwise therethrough, a channel shaped unitary floating sill structure in the guideway to project beyond opposite ends thereof and slidably supported from the underframe structure, and a hydraulic cushioning unit disposed in the floating sill structure in line with the guideway and including a double ended hydraulic cylinder lengthwise in the guideway and fixed to the floating sill structure and a double-ended piston and piston rod assembly slideable lengthwise in the cylinder to develop hydraulic fluid pressure therein, with the piston rods projecting from opposite ends of the cylinder to abut

with cooperating stops fixed to the underframe structure and projecting within the floating sill structure adjacent opposite ends of the assembly, said unit having means providing a hydraulic fluid flow path between opposite ends of the cylinder for developing fluid frictional resistance to relative lengthwise movement between the cylinder and the assembly so that the unit resists relative lengthwise movement between the structures by developing hydraulic fluid friction under hydraulic pressure.

- 10 11. In combination, an underframe structure having a guideway open at the bottom and extending lengthwise through the underframe structure, a channel shaped floating sill structure having an open bottom and supported from the underframe structure for lengthwise sliding movement in the guideway, said floating sill structure extending the length of said guideway and having aligned draft pockets adjacent opposite ends thereof, a draft gear mechanism operatively mounted in each pocket, coupling mechanism to each draft gear mechanism for transmitting buff and draft impact forces therethrough to the floating sill structure, and a double acting hydraulic cushioning unit disposed in the floating sill structure intermediately between and aligned with the draft pockets and including a double-ended hydraulic cylinder lengthwise of the guideway and fixed to the floating sill structure and a double-ended piston and piston rod assembly slideable in the cylinder to develop hydraulic fluid pressure therein, with the piston rods projecting from opposite ends of the cylinder to abut with cooperating stops fixed to the underframe structure and projecting within the floating sill structure adjacent opposite ends of the assembly, said unit having means providing a hydraulic fluid flow path between opposite ends of the cylinder for developing fluid frictional resistance to relative lengthwise movement between the cylinder and the assembly so that the unit resists relative lengthwise movement between the structures by developing hydraulic fluid friction under hydraulic pressure.
- 20 12. A cushion mechanism for a railway vehicle for absorbing the energy of an impact applied to a coupler thereof comprising, a vehicle body, a center sill structure extending longitudinally of said body and secured thereto, an auxiliary sill structure arranged for movements longitudinally relative to said center sill structure, a coupler and a draft rigging carried by each end portion of said auxiliary sill structure, means coupling said draft riggings to said auxiliary sill structure for moving the auxiliary sill structure relative to said center sill structure upon application of an impact to either coupler, a cylinder mounted within said auxiliary sill structure, a piston within said cylinder, a piston rod extending through opposite ends of said cylinder, liquid within said cylinder, a stop structure secured to said center sill structure in abutting relationship with one end of said piston rod, stop means carried by the center sill structure in abutting relationship with the other end of said piston rod, lugs carried by the auxiliary sill structure engaging opposite ends of said cylinder preventing longitudinal movements of the cylinder relative to the auxiliary sill structure, and said cylinder having grooves therein controlling the velocity of flow of the liquid from one side of the piston to the other to cushion movements of the auxiliary sill structure relative to the center sill structure.
